(57) **CLAIM**

The ornamental design for a drill for surgical instrument, as shown and described.

DESCRIPTION

FIG. 1 is a left side perspective view of a drill for surgical instrument showing our new design;

FIG. 2 is a right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof; and,

FIG. 9 is a referential view showing the drill being attached to a handpiece.

The features shown broken lines in the drawings depict environmental subject matter only and form no part of the claimed design.
